US00D993809S

(12) **United States Design Patent** (10) Patent No.: **US D993,809 S**
Rafaelian (45) Date of Patent: ** *Aug. 1, 2023

(54) **EXPANDABLE FLAT WIDE BAND
BRACELET**

(71) Applicant: **Carolyn Rafaelian**, Delray Beach, FL (US)

(72) Inventor: **Carolyn Rafaelian**, Delray Beach, FL (US)

(*) Notice: This patent is subject to a terminal disclaimer.

(**) Term: **15 Years**

(21) Appl. No.: **29/848,085**

(22) Filed: **Jul. 29, 2022**

(51) LOC (14) Cl. **11-01**

(57) **CLAIM**

The ornamental design for an expandable flat wide band bracelet, as shown and described.

DESCRIPTION

FIG. 1 is a perspective view of the expandable flat wide band bracelet in accordance with the present design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

1 Claim, 1 Drawing Sheet
